CLAIM

The ornamental design for a beverage container, as shown and described.

DESCRIPTION

FIG. 1 is a top perspective view of a beverage container showing my new design;

FIG. 2 is a bottom perspective view thereof;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

(Continued)

The broken lines in the drawing depict portions of the beverage container that form no part of the claimed design.

1 Claim, 3 Drawing Sheets
